UNITED STATES PATENT OFFICE.

CARBON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA.

PROCESS OF TREATING HYDROCARBONS.

Application filed September 29, 1919, Serial No. 327,315. Renewed March 24, 1927.

This invention relates to improvements in process of converting hydrocarbons and refers more particularly to an improved process and apparatus for converting heavy into lower boiling point hydrocarbons.

Among the objects of the invention are to provide a process by which the heavy hydrocarbons containing little or no gasoline content are so subjected to heat and pressure as to convert a substantial portion thereof into gasoline-like products; to provide a process of the character referred to in which the oil passes through a plurality of small streams in a cracking zone and thence to a vapor chamber located outside of the cracking zone so as to reduce to a minimum the danger of fires; to provide a process in which the reflux condensate is returned to the cracking zone for further treatment without being mixed with the heavier residue found in the vapor chamber; to provide a process which can be operated in a novel form of apparatus as a continuous process; to provide a process in which the condensed vapors which are to be retreated are delivered to the cracking zone either by gravity or by positive pump feed and in general to provide an improved apparatus and process of the character referred to.

In the drawings, the single figure designates a somewhat diagrammatic side elevation of my improved apparatus.

Referring to the drawings, 1 designates the fire box in which is mounted a series of inclined tubes 2 connected at their ends to the inlet headers 3 and outlet headers 4 respectively. The header 4 is connected through leg 5 to a vapor chamber 6 which vapor chamber 6 is mounted on suitable supports 7 so as to be outside of the fire zone. The vapor chamber 6 is provided with manholes 8 and 9 and draw off line 10, the latter leading to a residuum tank not shown and controlled by throttle valve 11.

The vapors pass through the goose neck 12 to a reflux aerial condenser 13 which aerial condenser 13 takes the form of a pair of cylindrical headers 14 and 15 connected by a plurality of zigzag aerial pipes 16. From the upper header 15, the vapors pass through lines 17 and 18 to the water condenser 19. From the water condenser 19, the condensed liquid and uncondensable gases pass to the receiving tank 20. This tank 20 is provided with gas outlet 21 and liquid draw off 22 con-

trolled by throttle valves 23 and 24 respectively. By regulating the valves 11, 23 and 24, any desired vapor pressure may be maintained on the system during distillation and condensation.

Fresh oil is delivered from supply tank 25 by means of pump 26 to the inlet header 3. This inlet header is connected by pipe 27 to branch pipe 28 leading to the pump 26. The valve 29 is interposed in line 28. The still may be charged with oil and the pump 26 operated with the valve 29 left open to feed a continuous supply of fresh charging stock to the cracking zone. As a feature of the invention means are provided for returning a certain part of the condensed vapors, to wit those that first condense or the heavier ones directly to the cracking zone and without comingling them with the residue in the chamber 6. This is accomplished by means of the depressed or U-shaped portion 30 in the goose neck 12, which U-shaped connection 30 leads to the charging line 27 by means of pipe 31. A pump 32 is interposed in the line 31 which is also provided with valve 33. By this means, the condensate may be forced directly by pump 32 into the charging line and comingled with the fresh supply of oil from pump 26. If desired, however, the condensate may by-pass the pump 32 which is accomplished by by-pass line 34 controlled by valve 35.

An illustrative run of the process may be described as follows: gas oil of say 32 degrees Baumé gravity from mid continent fields is fed continuously for example into the inclined tubes 2, forming the cracking zone. The oil is there heated to a temperature of say 750° to 850° F. and passes to the vapor chamber where the temperature may drop say 100° or more. The unvaporized oil in the chamber 6 is drawn off through the line 10 to a residuum tank and it is to be understood that this residue contains the greater part of the objectionable carbon content. By this means, the carbon content is prevented from returning to the pipes 2 in the cracking zone. The vapors pass out through the goose neck 12 through the aerial reflux condenser. The lighter portions thereof and the uncondensable gases pass into the water condenser and thence to the receiving tank 20. The heavier condensate, however, returns through the trap 30 and line 31 to the charging line and either passes to

the charging line by gravity through by-pass 34 or is pumped directly by means of pump 32 into this charging line.

The pressure may be from say 100 to 150 5 lbs. to the square inch and from 30 to 50% of the gas oil may be converted into 400 end point gasoline of say 56 to 58 degrees Baumé gravity. As we have stated this process can be operated as a continuous process. This 10 process can be successfully carried out in the cracking apparatus now in use and with relatively inexpensive changes, such changes however utilizing the novel features of my improved apparatus.

15 I claim as my invention:

A process of converting heavy into lighter hydrocarbon, consisting in continuously passing oil through a heating zone where it is subjected to a cracking temperature, in introducing the heated oil to an enlarged vapor 20

chamber, in discharging unvaporized residue from said vapor chamber and preventing it from again coming in contact with the incoming charging stock fed to said heating zone, in taking off vapors from said vapor chamber and passing them through a vapor line to a reflux condenser, in trapping all the condensate produced in said line to prevent any of said condensate from directly returning to the vapor chamber, in returning said condensate, together with condensate produced in the reflux condenser to the heating zone for retreatment, in condensing and collecting the vapors from said reflux condenser, and in maintaining a vapor pressure 35 above atmospheric on the oil undergoing conversion.
